DOOR

Louis Chartier, Schenectady, N. Y.

Application April 9, 1937, Serial No. 136,007

3 Claims. (Cl. 20—35)

My invention relates to improvements in doors, particularly automobile doors such as are used in buses, and the primary object thereof is to provide an inexpensive means for removably securing a glass panel in the door frame quickly and with a minimum expenditure of labor and material.

To the accomplishment of the above and subordinate objects presently appearing a preferred embodiment of my invention has been illustrated in the accompanying drawings, set forth in detail in the following description, and defined in the claims appended hereto.

In said drawings:—

Figure 1 is a view in side elevation of a door embodying my improvements.

Figure 2 is a view in vertical transverse section taken on line 2—2 of Figure 1 looking in the direction indicated by the arrows.

Figure 3 is a view in side elevation of a keeper frame forming part of my invention.

Figure 4 is a fragmentary view in side elevation looking at the opposite side of the door from that shown in Figure 1.

Figure 5 is a fragmentary view in transverse section taken on the line 5—5 of Figure 1 looking downwardly and drawn to an enlarged scale, and

Figure 6 is a view in perspective of a keeper strip for retaining the keeper frame in position.

Referring to the drawings by numerals, according to my invention the door frame 1, in this instance of rectangular form, is rabbeted around the inner edge thereof to provide a rectangular seat 2 and an abutment flange 3 on one side of the frame extending around the inner edge of the latter. The seat 2 is designed to receive the usual glass panel 4 which is retained in position on one side of the frame 1 by the aforesaid flange 3. At the side of the panel 4 opposite to the flange 3 the frame 1 is channeled around the inner edges 5 and 6, respectively and the top of said frame is cut away or reduced in thickness on the channeled side of said frame to a depth corresponding to the plane of the inner side of the channels 5 and 6 to thereby form a socket 7 into which the side channels 6 open, said socket having inwardly bevelled ends for a purpose presently seen. Mounted in the channels 5 and 6 to extend part way into the socket 7 is a rectangular keeper frame 8 of flat resilient metal overlying at its inner edges the opposed edges of the panel 4. The sides 9 of the keeper frame 8 have formed in their outer edges, substantially midway of said ends, bayonet slots 10 each receiving a pin 12 passing through the channeled part of the corresponding

side of the door frame 1 as best shown in Figure 5. The channels 5 and 6 are spaced slightly from the panel 4 and interposed between said panels and keeper frame 8 is padding strip 13 of felt or other suitable material extending completely 5 around said panel and retaining or keeper frame. The keeper frame 8 is held in the channels 5 and 6 by a keeper strip 14 secured in the socket 7 by means of screws 15 passing through said strips 14 and the frame 1 beyond the adjacent end of the 10 glass panel 4. As best shown in Figure 1 the keeper strip 14 overlaps the upper end of the keeper frame 8 for a purpose presently apparent and is formed with bevelled ends 16 fitting against the aforementioned bevelled ends of the socket 7 15 to prevent said strip from sagging and thereby destroying the continuity of the upper end of the structure.

When it is desired to assemble the described door structure, the glass panel 4 is placed in position on the seat 2 against the flange 3. The keeper frame 8 is then flexed or bowed, at its ends so that the sides 9 thereof may be inserted in the side channels 6, it being understood that during this operation the lower end of the keeper frame 20 is held above the bottom channel 5. Upon release of the flexed keeper frame 8, as will be clear the sides 9 thereof will spring into the side channels 6 against the pins 13. It may be stated at this point that the bayonet slots 10 and pins 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890

The foregoing constitutes a detailed description of a preferred embodiment of my invention and it is believed that advantages and operation thereof will be clear without further explanation. 55

It is to be understood, however, that the present disclosure is illustrative rather than restrictive and that right is herein reserved to changes and modifications in details described falling 5 within the scope of the claims appended hereto.

What I claim is:—

1. A door structure comprising a rectangular frame rabbeted around the inner edges of the bottom and sides thereof to provide a seat extending around said inner edges and a flange on one side of said seat, said seat being grooved to provide a bottom and side channels in said frame at one side of said flange, and the top of the frame on the channeled side thereof being reduced intermediate the side channels to form a socket into which said side channels open, a panel disposed in said frame against said seat, a rectangular keeper frame fitting in said channels and socket to overlie the edges of said panel 10 on the side thereof opposite said flange, said keeper frame being formed of resilient metal for bending at its ends to insert the sides thereof into the side channels and for reaction of said ends to spring the sides of the frame into the side channels, and a keeper strip removably secured in said socket and overlying the top edge of said keeper frame.
2. A door structure comprising a rectangular frame rabbeted around the inner edges of the bottom and sides thereof to provide a seat extending around said inner edges and a flange on one side of said seat, said seat being grooved to provide bottom and side channels in said frame at one side of said flange and the top of the frame 15 on the channeled side thereof being reduced intermediate the side channels to form a socket into which said side channels open, a panel disposed in said frame against said seat, a rectangular keeper frame slidably fitting into said channels and socket to overlie the edges of said panel on the side thereof opposite said flange, said keeper frame being formed of resilient metal for bending at its ends to insert the sides thereof into the side channels and for reaction of said 20 ends to spring the sides of the frame into the side channels, said keeper frame having a pair of bayonet slots in the outer side edges thereof, respectively, and the door frame having a pair of pins therein extending into the side channels and entering said slots as an incident to springing of said keeper frame, and a keeper strip removably secured in said socket and overlying the top edge of said keeper frame.

to overlie the edges of said panel on the side thereof opposite said flange, said keeper frame being formed of resilient metal for bending at its ends to insert the sides thereof into the side channels and for reaction of said ends to spring 5 the sides of the frame into the side channels, a keeper strip removably secured in said socket and overlying the top edge of said keeper frame, and a packing strip of resilient material interposed between said panel and the overlying edges of 10 said keeper frame.

3. A door structure comprising a rectangular frame rabbeted around the inner edges of the bottom and sides thereof to provide a seat extending around said inner edges and a flange on one side of said seat, said seat being grooved to provide bottom and side channels in said frame at one side of said flange, and the top of the frame 15 on the channeled side thereof being reduced in thickness intermediate the side channels to form a socket into which side channels open, a panel disposed in said frame against said seat, a rectangular keeper frame slidably fitting into said channels and socket to overlie the edges of said panel 20 on the side thereof opposite said flange, said keeper frame being formed of resilient metal for bending at its ends to insert the sides thereof into the side channels and for reaction of said 25 ends to spring the sides of the frame into the side channels, said keeper frame having a pair of bayonet slots in the outer side edges thereof, respectively, and the door frame having a pair of pins therein extending into the side channels and entering said slots as an incident to springing of 30 said keeper frame, and a keeper strip removably secured in said socket and overlying the top edge of said keeper frame.

LOUIS CHARTIER.
